INTERLOCKING STEEL SHEET PILING

Edwin Fenton Stevens, St. Paul, Minn.

Application January 31, 1936, Serial No. 61,711

1 Claim. (Cl. 61—58)

My invention relates to piling and particularly to double wall steel sheet piling.

Steel sheet piling is often used in constructing either temporary or permanent cofferdams, wells, dams, bridge piers and abutments, culvert walls and abutments, foundations and other types of walls where relatively strong and/or water-tight construction is required.

An object of my invention is to provide a type of steel sheet piling capable of forming an internally braced double wall.

Another object is to provide such steel sheet piling arranged to form a wall having interior spaces which may be filled as with concrete, earth, sawdust, cinders or other material.

These and other objects and advantages of the invention will be more fully set forth in the following description made in connection with the accompanying drawings, in which like reference characters refer to similar parts throughout the several views, and in which:—

Fig. 1 is a top plan view of a short section of a wall assembled from one form of my piling;

Fig. 2 is a broken partial elevation view of the wall shown in part in Fig. 1;

Fig. 3 is a top plan view of a second form of my piling;

Fig. 4 is a top plan view of a short section of a wall assembled from a third form of my piling and filled with concrete or the like;

Fig. 5 is a top plan view of a fourth form of my piling;

Fig. 6 is a top plan view of a fifth form of my piling;

Fig. 7 is a top plan view of a sixth form of my piling;

Fig. 8 is a top plan view of a seventh form of my piling;

Fig. 9 is a top plan view of a form of my pile unit for use at corners in a wall;

Fig. 10 is a top plan view of other forms of pile units for use at corners, and

Fig. 11 is a top plan view of an eighth form of my piling.

In general my piling consists of elongated units of a length corresponding to the vertical dimension or height of walls to be constructed from a plurality thereof and having interlocking elements whereby adjacent units of piling forming a portion of a wall may be longitudinally driven, jetted or slid into interlocking relation in the usual manner employed in placing ordinary steel sheet piling. My units may, of course, be made in various lengths so as to provide for walls of various desired heights.

Referring to the drawings and particularly to Figs. 1 and 2, one form of my piling includes an I-beam 1 having flanges 1a. A pair of elongated rectangular plates 8, disposed parallel to the I-beam 1 and each other, are secured to the flanges 1a of the I-beam 1 by suitable means such as the rivets 8a with their longitudinal center lines in the plane of the web of the I-beam 1. Each of the longitudinal free edge portions of the plates 8 is provided with interlocking elements 9 of the type commonly used on interlocking steel sheet piles. All of the respective interlocking elements 9 are disposed with like ends uppermost, so that the interlocking elements 9 on facing edges of respective adjoining pile units 5 of a wall formed thereof are complementary to each other.

The corner unit shown in the right hand portion of Fig. 1 is constructed in the same manner as the straight wall units shown to the left thereof with the exception that the elongated rectangular plates 8b and 8c are of suitable dissimilar widths and are each bent at right angles along lines parallel to and near to the longitudinal center lines of the plates. Obviously, if a corner of other than 90 degrees is desired, the angle to which the plates 8b and 8c are bent may differ from a right angle in accordance with the desired angle of the corner.

In constructing a wall with my pile units, each successive unit is first placed with the lower ends of one pair of the interlocking elements 9 thereof aligned with the upper ends of the unoccupied pair of interlocking elements 9 of the previously installed pile unit and is then driven downwardly 20 to the same level as the previously installed unit or to the desired level so as to telescope the aligned interlocking elements 9 of the respective pile units into fully engaged relation with each other.

The form of my interlocking pile shown in Fig. 3 consists of an H-beam 10 having interlocking elements 11 on the free edges of each of its respective flanges. The interlocking elements 11 on the respective flanges formed on one edge of the web of the H-beam 10 are disposed with like ends uppermost and the interlocking elements 11 on the respective flanges formed on the other edge of the web have ends disposed uppermost which are alike but which are opposite to the uppermost ends of the interlocking elements 11 on the first mentioned flanges, as shown.

The form of my piling shown in Fig. 4 is similar to the form shown in Fig. 3 except that the interlocking elements 13 on the flanges of its H-beam 55

are somewhat differently arranged. The respective interlocking elements 13 on the pair of flanges extending from the web of the H-beam in one direction are disposed with like ends uppermost and the interlocking elements 13 on the remaining pair of flanges are disposed with ends uppermost which are opposite to the uppermost ends of the first mentioned elements. With such an arrangement of interlocking elements each 10 pile unit, when driven in forming a wall, is so disposed that the upwardly facing end thereof is the end corresponding to the downwardly facing end of the preceding pile unit.

In Fig. 4 the interior spaces formed in a wall 15 built of my piling units are filled with material 14, such as concrete, earth, sawdust, cinders or any other desired material. The material with which the spaces are filled acts very effectively to strengthen the wall and to seal the joints 20 therein. The forms of my piling shown in Figs. 1, 2, and 3 and the forms shown in Figs. 5 and 6 and to be described are, of course, adapted for filling in the same manner. One interior space of the piling shown in Fig. 1 is shown so filled 25 with material 14.

The form of my piling shown in Fig. 5 is similar to the form shown in Fig. 4 except that the interlocking elements 13 of diagonally opposite flanges are omitted. The flanges not having interlocking elements thereon may be of any desired width ranging from the full width shown in Fig. 5 down to a width approaching zero.

The form of my piling unit shown in Fig. 6 is similar to that of Fig. 1 relative to the arrangement of its interlocking elements 15 and is similar to the forms of Figs. 3 and 4 in that the interlocking elements 15 are carried by an H-beam 14. However, the interlocking elements 15, instead of being formed integrally with the 40 H-beam 16, are formed with mounting flanges 15a which are secured to the marginal free edge portions of the respective flanges of the H-beam 14 by suitable means such as the rivets 17.

Referring to Fig. 7, the form of piling shown 45 therein is substantially the same as the pile unit shown in Fig. 3 except that two webs 18 are provided in place of the single web 10 of Fig. 3.

The form of pile unit shown in Fig. 8 is similar to the pile unit of Fig. 7 except that a web-like 50 brace 19 of X-shaped cross section is provided in place of the two webs 18 of Fig. 7.

The corner unit of Fig. 9 includes a pair of elongated rectangular plates 20 and 21 bent at right angles or any other desired angles along 55 lines parallel to their respective longitudinal axes and having an interlocking element 22 formed along each longitudinal free edge thereof. Webs 23 extend from the bend of the narrower plate 21 in line with the respective angularly extending portions thereof to the inner side of the wider plate 20 to meet the same at right angles thereto. The webs 23 are secured along their longitudinal edges to the portions of the plates 20 and 21 60 abutted thereby.

Fig. 10 illustrates another form of my piling 65 for use at corners in walls. The left-hand unit thereof is the same as the previously described unit shown in Fig. 3. The lower unit thereof is the same as the unit of Fig. 3 except that one

flange 10a of the H-beam 10 is somewhat wider than the other flanges and is bent outwardly at right angles a short distance inwardly of the interlocking element 11 thereof as shown. The remaining unit consists of an elongated rectangular plate 24 bent at right angles along a line parallel to its length and having an interlocking element 25 formed on each longitudinal edge thereof. The space within the corner structure formed by the above described units 10 may be filled with any desired filling material 14 as indicated in the drawings. If desired, the angular bends referred to above may be made at other angles than right angles.

Fig. 11 illustrates another form of my pile unit 15 comprising a pair of elongated rectangular plates 26 secured to each other by suitable means in longitudinal portions thereof intermediate their free edges in slightly spaced parallel relation to each other, the spacing being provided by suitable spacers 27. The portions of the respective plates 26 extending laterally in a common direction from the longitudinal portions at which the plates are secured to each other diverge outwardly and are provided at their longitudinal 25 edges with longitudinally extending interlocking elements 28. The corner unit shown in the right hand portion of Fig. 11 is the same as the straight wall unit to its left except that each of the elongated rectangular plates 29 and 30 thereof is bent 30 at a right angle on a line extending longitudinally thereof as shown and that the outer plate 29 is of slightly greater width than the inner plate 30. The bends in the plates 29 and 30 may, of course, be made at angles other than right angles if desired. Also the spaces within a wall formed of the pile units illustrated in Fig. 11 may be filled with any suitable filling material 14 if desired.

In all of the forms of my piling unit the webs 40 thereof provide much greater strength and rigidity in a wall formed of my piling units than can be obtained in a single wall formed of ordinary steel sheet piling.

It is apparent that I have invented a novel and 45 improved type of interlocking, double wall steel piling having great strength and rigidity and providing interior spaces adapted for filling with concrete or other material.

It will, of course, be understood that various 50 changes may be made in the form, details, arrangement and proportions of the parts, without departing from the scope of my invention, which, generally stated, consists in a device capable of carrying out the objects above set forth and in 55 the novel parts and combinations of parts disclosed and defined in the appended claim.

What is claimed is:—

Interlocking double walled metal piling comprising a plurality of interconnected pile sections, 60 each section comprising a pair of long channel-like members having central webs closely spaced from each other and each member having outwardly diverging side webs, said side webs terminating in continuous edge interlocking elements and means securing together the central webs of the pair in closely spaced parallel relation.

EDWIN FENTON STEVENS.
